UNITED STATES PATENT OFFICE.

RHYS F. LEWIS, OF WILKES-BARRE, PENNSYLVANIA.

COAL-SCUTTLE.

SPECIFICATION forming part of Letters Patent No. 284,030, dated August 28, 1883.

Application filed January 31, 1883. (Model.)

To all whom it may concern:

Be it known that I, RHYS FREDERICK LEWIS, of Wilkes-Barre, in the county of Luzerne and State of Pennsylvania, have invented a new and useful Improvement in Coal-Scuttles, of 5 which the following is a full, clear, and exact description.

Reference is to be had to the accompanying drawings, forming part of this specification, 10 in which similar letters of reference indicate corresponding parts in all the figures.

Figure 1 is a side elevation of my improvement partly in section. Fig. 2 is a sectional plan view of the same taken through the line 15 *x x*, Fig. 1. Fig. 3 is a sectional elevation of a part of the bottom of the same, taken through the line *y y*, Fig. 2.

The object of this invention is to facilitate 20 the insertion of coal in the fire-boxes of cooking-stoves.

A is the body of the scuttle, which is provided with a bail, *B*, a side handle, *C*, and a cover, *D*. The lower end of the scuttle *A* is made of such a size as to fit into a boiler-hole 25 of the stove-top, and has a flange, *E*, formed around it, near its lower edge, to rest upon the top of the stove. The bottom *F* of the scuttle *A* is placed at a little distance above the lower edge of the said scuttle, and has a rectangular opening formed through it, which is 30 provided with a downwardly-projecting flange, *G*. In the inner surface of the opposite sides of the flange *G* are formed inclined grooves *H* to receive the side edges of the valve *I*, which passes in through a slot, *J*, in the third 35

side of the flange *G*, and through a slot, *K*, in the side of the scuttle *A*, below the bottom *F* and above the flange *E*, as shown in Fig. 1. The outer end of the valve *I* is provided with a handle, *L*, for convenience in operating the 40 said valve.

In using the scuttle, it is placed in a boiler-hole of the stove, with the flange *E* resting upon the stove-top. The valve *I* is then opened and the coal is allowed to flow into 45 the fire-box. When the desired amount of coal has entered the fire-box, the valve *I* is closed and the scuttle is removed from the stove.

With this construction no coal dust or ashes 50 can escape into the room while the stove is being supplied with coal, and no coal will be spilled upon the stove or floor during the operation.

I am aware that coal-scuttles have been 55 formed with pivoted bottoms supported on a spring-catch, also with sliding bottoms; but What I do claim as new and of my invention is—

In a coal-scuttle, the body *A*, having slot *K*, 60 and the valve *I*, extending through said slot, in combination with a rigid bottom, *F*, having rectangular flange *G*, grooved diagonally at *H H* on opposite sides, and slotted at *J*, as shown and described.

RHYS F. LEWIS.
